MORITZ SCHENKEL, OF BERLIN-CHARLOTTENBURG, GERMANY, ASSIGNOR TO WESTINGHOUSE ELECTRIC & MANUFACTURING COMPANY, A CORPORATION OF PENNSYLVANIA.

VAPOR ELECTRIC DEVICE

Application filed July 2, 1930, Serial No. 465,381, and in Germany July 4, 1929.

My invention relates to vapor-electric devices and particularly to cathodes for such devices.

In the operation of vapor electric apparatus, such as mercury-arc rectifiers, it has been found desirable to maintain the cathode spot in substantially a fixed position. Various expedients have been restored to maintain the cathode spot in a fixed position, among which has been the use of a metallic pin projecting above the mercury, but this has been unsatisfactory because the heat of the cathode spot is sufficient to fuse most metals. Also, cathodes having very small mercury surfaces have been used, but it has been found that, in such cathodes, the mercury is not sufficient to carry away the heat generated at the cathode spot.

In addition to desiring a fixed cathode spot, it is also desirable to reduce, as much as possible, the vapor pressure in a vapor-electric device.

My invention contemplates the use of a funnel-shape cathode shield having a perforation to maintain the cathode spot in a fixed position. Experiments have shown that the evaporation of mercury does not occur at the spot directly impinged by the rectifying arc but at a point that the cathode spot has just left or, if the cathode spot is fixed, from the region immediately around it. I believe that this lack of evaporation at the cathode spot is caused by the positive ions bombarding the surface of the mercury at such spot and retaining the evaporating mercury in a purely mechanical manner. As my funnel-shape shield maintains the cathode spot in a fixed position and, as the mercury vapor arises from the surface of the mercury around the cathode spot, I find it possible to deflect the rising mercury vapor into contact with a cooler placed immediately above the surface of the cathode, and, consequently, to condense the mercury vapor before it rises into the main portion of the device.

Other objects and advantages will be apparent from the following detailed description, taken in conjunction with the accompanying drawing, in which,

Figure 1 is a sectional elevation of a por-

tion of a vapor-electric device comprising my invention, and

Figs. 2 and 3 are similar views of modifications of the same.

The apparatus disclosed in the drawing 55 comprises a tank 1, such as the metal tank of a mercury-arc rectifier. A cathode dish 2 is insulated from the tank in any desired manner, as by a ring insulator 3. A vaporizable cathode material 5, such as mercury, is placed in the cathode dish 2. A funnel-shaped shield 10 is placed immediately above the surface of the mercury. The spacing between the bottom of the shield 10 and the surface of the mercury should, preferably, be just sufficient to avoid wetting the shield when the mercury is disturbed by the impact of the rectifying arc. The small end opening 11 in the shield 10 should be of approximately the same size as the maximum size 60 of the cathode spot. However, in some cases, the size of the cathode spot may be somewhat smaller than the necessary size of the starting anode. In such case, the opening 11 must be sufficiently large to pass the tip 65 of the starting anode 12. The overall size of my funnel-shape shield should be sufficient to cover the surface of the mercury and prevent the possibility of the arc striking past the shield to an exposed mercury surface. 70 However, the shield must be separated from the wall of the tank sufficiently to allow condensed mercury to flow back to the cathode 75 outside of the shield. The shield itself is preferably made of insulating material in order to prevent the arc striking any portion 80 of it.

As the evaporation from the cathode spot is comparatively small, when compared with the evaporation from the surface of the cathode material adjacent to the cathode spot, it is apparent that the mercury vapor, rising from the cathode surface, will strike against the under-surface of the shield and pass 85 around it in order to reach the main portion of the device. I take advantage of this deflection of the mercury vapor to condense it before it can enter the main portion of the device. To this end, I place coolers 15 between the surface of the mercury and the 90 95 100
